[57] **CLAIM**

The ornamental design for hand held medical computer carrying case, as shown and described.

DESCRIPTION

FIG. 1 is a perspective view of the hand held medical computer carrying case with a hand-held computer held therein;

FIG. 2 is a top view of FIG. 1;

FIG. 3 is the top view of FIG. 1 without a hand-held medical computer held therein;

FIG. 4 is a front view of FIG. 3;

FIG. 5 is a back view of FIG. 3;

FIG. 6 is a side view of FIG. 3;

FIG. 7 is a bottom view of FIG. 3; and,

FIG. 8 is a bottom perspective view of FIG. 3.

The hand-held computer depicted by means of broken lines in FIGS. 1 and 2 has been shown for environmental purposes only and forms no part of the claimed design.
